(57) **CLAIM**

The ornamental design for a display stand, as shown and described.

DESCRIPTION

FIG. 1 is a front elevation view of a display stand shown in a closed configuration according to a first embodiment; FIG. 2 is a rear elevation view thereof;

FIG. 3 is a left side elevation view thereof in the closed configuration;

FIG. 4 is a right side elevation view thereof;

FIG. 5 is a top plan view thereof;

FIG. 6 is a bottom plan view thereof;

FIG. 7 is a front, top, and right perspective view thereof; FIG. 8 is a rear elevation view of the display stand according to the embodiment of FIG. 1 shown in an open configuration;

FIG. 9 is a front, top, and right perspective view of the display stand according to the embodiment of FIG. 1 shown in an open configuration;

FIG. 10 is an environmental perspective view of the display stand according to the embodiment of FIG. 1 shown in an open configuration supporting a monitor of a laptop computer;

FIG. 11 is a left side elevation view of the display stand in the open configuration of FIGS. 9 and 10, without the environmental laptop computer;

FIG. 12 is a front elevation view of a display stand shown in a closed configuration according to a second embodiment; FIG. 13 is a rear elevation view thereof;

FIG. 14 is a left side elevation view thereof in the closed configuration;

FIG. 15 is a right side elevation view thereof;

FIG. 16 is a top plan view thereof;

FIG. 17 is a bottom plan view thereof;

FIG. 18 is a front, top, and right perspective view thereof; FIG. 19 is a rear elevation view of the display stand according to the embodiment of FIG. 12 shown in an open configuration;

FIG. 20 is a front, top, and right perspective view of the display stand according to the embodiment of FIG. 12 shown in an open configuration;

FIG. 21 is an environmental perspective view of the display stand according to the embodiment of FIG. 12 shown in an open configuration supporting a monitor of a laptop computer; and,

FIG. 22 is a left side elevation view of the display stand in the open configuration of FIGS. 20 and 21, without the environmental laptop computer.

(Continued)

The broken lines show environmental features in FIGS. 10 and 21 and portions of the display stand in FIGS. 12-22 that form no part of the claimed design.
